GAS GENERATION SYSTEM

Frank L. Oppenheimer, University Heights, Roy C. Schweitzer, Highland Heights, and Robert S. Mathias, Kirtland, Ohio, assignors to Thompson Ramo Woolridge Inc., Cleveland, Ohio, a corporation of Ohio

Filed Oct. 20, 1960, Ser. No. 63,793

6 Claims. (Cl. 60—39.48)

This invention relates to gas generation systems and more particularly to improved methods and means for generating gases and controlling the flow of the gas producing fuel to the gas generator.

Heretofore, typical gas generation means employed with missiles, rockets and the like have been self-contained. Such gas generation means normally comprised a gearbox-driven fuel pump which provided fuel to the gas generator after the gas generation system had been started. Use of fuel pumps has the inherent disadvantage in such self-contained gas generation systems of "bootstrap" starting. System operation had to reach a certain level before the pump could independently provide fuel at the required pressure and flow rate to maintain the system operable. Thus, quick starting of the systems was virtually impossible unless an outside, independent and ground-supplied power source was used to initially drive the fuel pump.

In addition to the above disadvantage, present-day monofuels require purging of the gas generator to clear the system of fuel which is ignitable at the high heat levels remaining after system shut-down. Consequently, restart of the system was prevented because, in the purging operation, the pressurizing medium supply for the fuel tank was exhausted.

With the present invention, we substantially eliminate the problems and difficulties of the prior art and provide self-contained gas generation systems which are operable for extended durations, levelly re-startable, quick starting and self-contained.

It is therefore an object of the present invention to provide improved auxiliary power supply systems for rockets, missiles and related air and space-borne vehicles.

It is another object of the present invention to provide self-purging and quick starting auxiliary power supply systems for rockets, missiles and related air and space-borne vehicles.

It is still another object of the present invention to provide re-startable and self-contained gas generation systems having improved fuel control means.

It is another object of the present invention to provide improved auxiliary power supply systems operatively responsive to the output of the system for control of the fuel supply.

It is a further object of the present invention to provide improved modulating valve means adapted to control fuel flow to the gas generator of auxiliary power supply systems without the requirement for a fuel pump.

It is another object of the present invention to provide improved methods for generating gases for operation of auxiliary components of missiles, rockets and related air and space-borne vehicles which are self-controllable.

Another object of the present invention is to provide improved gas generation apparatus which is simple and compact in construction and high speed and efficient in operation.

These and other objects, features and advantages of the present invention will become more apparent from a careful consideration of the following detailed description when considered in conjunction with the accompanying drawings illustrating a preferred embodiment of the present invention and wherein like reference numerals

2

and characters refer to like and corresponding parts throughout the several views.

On the drawings:

FIGURE 1 is a generally schematic view of a preferred embodiment of the gas generation system of the present invention.

FIGURE 2 is a block diagrammatic view of the control means for the fuel flow modulating valve.

FIGURE 3 is a view in partial section of the preferred embodiment of the modulating valve of the present invention.

FIGURE 4 is a fragmentary view in partial elevation of the cam means controlling operation of the modulating valve.

FIGURE 5 is a view taken along lines V—V of FIGURE 3.

FIGURE 6 is a schematic view illustrating the operation of the modulating valve of FIGURE 3.

FIGURE 7 is a view taken along lines VII—VII of FIGURE 3.

As shown on the drawings:

As appears in FIGURE 1, a preferred embodiment of a gas generation system of the present invention may include a plurality of containers 7 to provide a source of an inert pressurizing medium, such as nitrogen, connected by a conduit 8 and a pressure regulator 8a of conventional construction to a monofuel containing tank 9 for pressurization thereof to feed the monofuel through a conduit 10 to the reaction chamber of a gas generator 11. Connected in conduit 10 is a normally closed fuel shut-off valve 12 energizable from a remote source, such as the autopilot system (not shown) of the air or space-borne vehicle with which the gas generation system is employed and from the ground control console (not shown), and a normally opened fuel flow modulating valve 13 for control of the rate of flow of fuel to the reaction chamber of the gas generator 11, the operation and construction of the modulating valve being described in detail hereinafter.

The chamber of the gas generator 11 is connected through a gas discharge outlet 14 to the turbine chamber of a turbine housing 15 for driving of the turbine 16. The turbine 16 is connected through its shaft to reduction gearing 17 and reduction gearing 17 may be

connected to one or more drive shafts 18 and 19 of auxiliary components 18a and 19a respectively, such as air conditioning units or fan pumps, of the vehicle with which the gas generation system is employed and to the shaft 20a of a conventional axial impeller type gas pump 20 for operation thereof.

Thus a conventional monofuel may be fed under pressure through the modulating valve and initially ignited hypergolically with a suitable oxidizer, such as nitric acid, introduced into the gas generator by conventional means (not shown) and the gaseous products of reaction exhausted through the discharge nozzle 14 into the turbine chamber to drive turbine 16 and the gearing 17, shafts 18, 19 and 20a and the components coupled thereto. The major portion of the exhaust gases exit through an outlet 21 to the atmosphere and the remainder of the exhaust gases by-pass through a conduit 22 connecting the turbine housing to a conduit 23. Connected in conduit 23 is a conventional heat exchanger 24 for cooling of the exhaust gases and a gas filter 25. Conduit 23 connects the turbine housing through the heat exchanger 24 and filter 25 to the gas pump 20. Thus, the cooled and filtered exhaust gases are flowed from the gas pump 20 under a pressure substantially equal to the required pressure in the fuel tank pressurizing bottles 7 and at a rate controlled by the gas pump. Operation of the gas pump may also be controlled by an electric motor or other conventional means (not shown). From the gas pump 20 the

70

cooled and filtered exhaust gases flow into a conduit 26 under the influence of the gas pump. Conduit 26 is connected through a one-way check valve 27 to the fuel tank pressurizing medium outlet 7a and from the outlet 7a the exhaust gases flow into line 8 for pressurization of the fuel tank 9.

Thus a "boot-strap" replenishment system is provided for the fuel tank pressurization system and the requirement for an auxiliary fuel pump and gas purge system are eliminated. The elimination of these components constitute features of the present invention.

As appears in FIGURES 3-5 and 7 the modulating valve assembly, generally indicated by the numeral 13 may include a housing 30 chambered as at 31 in communication with the inlet side 10a and outlet side 10b of conduit 10. The housing 30 is provided with a removable boss 32 used for instrumentation and inspection and is secured to housing 30 as by screws 33, and a seal 34 may be employed to effectively prevent leakage of fuel from the chamber 31. Boss 32 is passaged as at 35, and the passage 35 is adapted for connection to an appropriate fitting.

Housing 30 is passaged also as at 38 in communication with the chamber 31 to receive a threaded sleeve fitting 39. The passage 38 is counterbored to provide a shoulder 41 as a seat for the sleeve 39. Sleeve 39 may be grooved to receive seals 42 and 43. A passage 44 is formed in the sleeve 39 to communicate the sleeve and chamber 31.

At a position directly opposite the sleeve 39 is passage 45 in housing 31 adapted for connecting chamber 31 to an appropriate fitting (not shown) at the outlet side 10b of conduit 10 to permit communication between the chamber 31 and conduit 10 (FIGURE 1).

The housing chamber wall 46 is passaged to receive a sleeve 47 having an outwardly flaring annular flange 47a which cooperates with a shoulder 46a of the chamber wall counterbore 46b to seat a seal 48. The housing wall 46 is grooved to receive a seal ring 49 and, for securing sleeve 47. Associated with the modulating valve is a conventional 115 VAC servo motor 51 operatively responsive to a signal received from the control system 100, shown in FIGURE 1, to vary the rate of flow of monofuel to the gas generator 11.

Shaft 52 passes through a guide 53 in sleeve 47 and extends into chamber 31 to form an offset crank cam 54 (FIGURES 3 and 4) for purposes hereinafter more fully described. A bearing 55 is employed for shaft 52 and is secured against a shoulder 56 of the sleeve 47 by pressure of the monofuel in chamber 31.

Shaft 52 extends a distance into chamber 31 and forms an offset crank to give desired cam action, as clearly appears in FIGURES 5 and 4.

The offset 54a of the cam, 54, is rectangular in cross-section and is integral with and perpendicular to the generally cylindrical leg 59 of the cam. The leg 59 is sized to a bearing 60 (FIGURES 3 and 5) and is provided with an annular groove 61 to receive a complementary retaining ring 62 which cooperates with a circular flange washer 63 carried by the cam means 54 to maintain the bearing in the desired position (FIGURES 3 and 4).

A metering pin cam guide track 64 is provided with slot 64a across the entire width of the guide to receive the bearing 60 and cam leg 59. The retaining ring 62 and retaining flange 63 maintain the bearing 60 and cam leg 59 in the slot 64a.

As appears in FIGURES 3 and 5 the cam guide 64 is an integral part of metering piston 66 which is positioned for limited sliding engagement in the passage 44 of the sleeve 39. As appears in FIGURES 3 and 7, the shaped metering piston 66 is provided with three flat surfaces 66a, 66b and 66c. Each surface 66a, 66b and 66c terminates inwardly of the sides 67, 68 and 69, of the piston and each of said surfaces is inwardly tapered, the taper ter-

minating at points 120° apart on the diameter of piston 66 to form a three sided guide for piston 66 to slide in sleeve 39. The surfaces 67, 68 and 69 form frusto-conical segments in piston 66 (FIGURE 7).

Formed in the piston 66 on three sides at 120° spacing are three circular chord passages 70, 71 and 72 defining with the inner wall of the sleeve passage 44 three fuel flow paths. Passages 70, 71 and 72 are each tapered outwardly a short distance from the end of the piston adjacent the cam guide and are of equal area over their major length adjacent the conduit inlet 10a (FIGURE 3). Thus communication is permitted through the flow passages 70, 71 and 72 between the conduit 10 and chamber 31. The total area of the flow path defined by the passages 70, 71 and 72 may be varied, because of the taper of the passages, by moving the piston 66 in the sleeve 39.

Movement of the piston 66 is accomplished by rotation of the shaft 52 which in turn moves the cam means 54 and cam guide 64 connected to piston 66 to the right as viewed in FIGURE 5. Movement of the cam guide 64 causes movement of the piston 66 and because of the taper thereof increases the total cross-sectional flow path in the sleeve 39 thereby varying the flow rate in and out of chamber 31. It will be appreciated of course that the piston is initially positioned in the sleeve 39 so that the total flow area in the sleeve is at a minimum. The contour of the passages 70, 71 and 72 are so shaped that the fuel flow paths defined by the sleeve 39 and piston passages 70, 71 and 72 are of variable total area at any cross-section across the tapered sides 67, 68 and 69.

Additionally, shaft 52 and piston 66 cooperate to maintain the cam guide 64 in spaced relation to the walls of the chamber 31.

Linear angular motion of shaft 52 will produce non-linear movement of the piston 66 in the sleeve passage 39 and therefore, will vary non-linearly, the area of the open fuel flow path defined by the sleeve passage walls and the piston. Linear control of the rate of flow of the fuel to the gas generator from the chamber 31 via conduit 10 is performed by non-linear area variation through the piston 66 coupled with a linear pressure drop between points 10a and 10b of conduit 10.

The modulating valve 13 is capable of metering fuel flow to the gas generator 11 without requiring a fixed pressure drop across the metering sleeve thereby permitting utilization of a pressurized fuel system and the elimination of the requirement for a fuel pump.

The fuel flow, from the laws of fluid dynamics, is a function of several variables in accordance with the following formula:

$$W_f = CA\sqrt{2gp\Delta P}$$

where:

W_f =fuel flow rate, lb./sec.

C =coefficient of discharge, constant

A =area of valve opening, in.²

g =gravitational force, in./sec.²-constant

ρ =density, lb./in.³-constant

ΔP =pressure drop across valve opening, lb./in.²

In many applications, the pressure drop across a valve opening is held constant; therefore, fuel flow varies directly with the area of the valve opening. However, in the present application, the pressure drop across the valve opening defined by the sleeve and passages of the piston 66 cannot be held constant because the present pressurized system does not require a low pressure sump normally required by pressure regulators and variations in gas generation result in varying pressure drops across the modulating valve. Accordingly, the modulating valve assembly 13 must control fuel flow by changing area to compensate for varying pressure drop across the valve. In accordance with the practice of the present invention, the chamber pressure in the gas generator 11 will increase with increasing fuel flow thereto. This pressure drop across the modulating valve decreases with increasing fuel

flow since the valve upstream pressure is maintained constant by the pressure regulator 8a. It will be appreciated that the pressure regulator is calibrated to provide a minimum flow rate to the gas generator 11 at least equal to the burning rate of the monofuel in the chamber to prevent burnback in conduit 10. The shape and total flow area defined by the piston 66 and sleeve 39 to maintain the fuel flow rate according to the required pressure drop-flow area relationship will vary depending upon these requirements. Such requirements are well within the skill of the art.

The modulating valve 13 is controlled by a control system which may include a tachometer generator 101 coupled to the turbine 16 through gearing 17 so that the frequency of the generator 101 is identical or proportional to the frequency or the output of the gas generator 11.

The output of the tachometer 101 is coupled through the modulating valve control system 100 which includes a frequency discriminator system 103 which feeds an output that has a sign and amplitude which are a function of the variation in frequency between the output of the tachometer 101 and a pre-selected standard control or reference frequency. As appears in FIGURE 2, the frequency discriminator 103 feeds an error signal to a magnetic amplifier 105 or the like as a preferred form of control device which, in turn, provides its output to the torque motor 51 coupled to the modulating valve. The error signal is converted in the torque motor shaft to a mechanical error signal which operates the torque motor shaft 52 and rotates the shaft in the desired direction to thereby control the flow pressure in the chamber 31 by movement of the cam and cam housing 64 and associated piston 66. Thus effective means are provided for controlling the rate of flow of fuel to the gas generator 11. A "feed back" network 106 is coupled to measure modulating valve fuel flow rate upstream of the gas generator 11. The feed back network feeds its output voltage which is proportional to the modulating valve velocities to the magnetic amplifier 105 for control of the amplifier system 105. An appropriate valve control system readily adaptable to the present invention is disclosed in U.S. Patent No. 2,790,091 issued on the application of Chatman et al.

In operation, the tachometer generator 101 supplies the signal to the frequency discriminator 103 which has an output potential proportional in sign and amplitude to the deviation of the speed of the turbine from the no load speed setting or pre-established proper operating frequency of the system. If the speed is low due to the application of a load by the accessory components 18 and 19, the magnetic amplifier 105 feeds a signal to the torque motor shaft which in turn rotates, and in rotating, moves the cam 54 and cam housing 64 to the right in FIGURE 5 thereby increasing the cross-sectional area of the fuel flow path defined by the piston 66 and sleeve 39 to increase the rate of fuel flow to the gas generator 11. The continued existence of the error signal operates to maintain this desired fuel flow rate by maintaining the piston in the required position relative to the sleeve 39. If on the other hand the modulating valve control system 100 senses an increase in turbine speed over the pre-selected value an error output is produced to return the torque shaft to the desired position thereby moving the cam housing 64 and piston 66 to the left until the desired pre-selected turbine speed is obtained whereupon the cam housing 64, piston 66 and cam 54 are in the position shown in section in FIGURE 5. The "feed back" signal derived through the "feed back" network 106 is employed to control operation of the magnetic amplifier in accordance with well known principles.

In operation, an electrical start signal from a ground start console (not shown) activates the pressure regulator 8a to admit the required amount of pressurizing medium from the gas containers 7 to the fuel tank 9 through line 8. Simultaneously, the electrical start sig-

nal may open the fuel shut-off valve 12 and the monopropellant fuel is fed from the fuel shut-off valve to the fuel modulating valve, which is in the full open position, the rate of flow of the fuel to the gas generator being controlled by the modulating valve 13. The initial position of the modulating valve piston 66 is in the full open position shown in FIGURE 5. The fuel is initially ignited hypergolically by contact with an acid oxidizer such as fuming nitric acid admitted through conventional means (not shown) to the gas generator 11. Control of the proportion of the acid fed to the gas generator is from the ground console (not shown). Once reaction conditions are established in the gas generator, the supply of the acid to the gas generator is terminated and the monofuel reacts to produce the gaseous products of reaction. The gases then flow through the outlet 14 for driving turbine 16 and a portion of the gases are exhausted through the conduit 21. The remainder of the exhaust gases flow through the outlet 22 through line 23 where it is cooled in the heat exchanger 24 and filtered in the filter 25. The gas then flows through the gas pump 20 operated by the gearing 17 and flows through the conduit 26 and check valve 27 for maintaining the pressure level in the containers 7 and providing means for continuing feed of the mono-propellant from the fuel tank 19 through the line conduit 10 to the gas generator 11. The tachometer 101 and control system 100 control, through the torque motor 51, the operation of the modulating valve 13 to assure that the pre-selected fuel feed rate to the gas generator 11 is maintained in accordance with the practice outlined above.

The gas generation system of the present invention is self-contained, is provided with a fuel flow rate control system operable over a range of fuel flow rate and includes a self-operable system for replenishing the fuel tank pressurization medium. The requirements for a fuel pump and an auxiliary purge system are eliminated.

Although various minor modifications might be suggested by those versed in the art, it is to be understood that we wish to embody within the patent warranted hereon all such embodiments as reasonably and properly come within the scope of our contribution to the art.

We claim as our invention:

1. A gas generation system comprising:
45 a source of fuel,
gas generation means,
a source of a pressurized medium,
first conduit means connecting the source of pressurized medium and the source of fuel to pressurize said fuel,
50 a pressure regulating valve connected to said first conduit means to regulate the flow of the pressure medium to the fuel source to supply the fuel source with a constant predetermined pressurization level,
55 a second conduit means connecting said source of fuel with said gas generation means to deliver fuel to said gas generation means,
means connected to the gas generation means to deliver a portion of the discharge gas from the gas generation means to the source of pressurized medium to maintain the supply of pressurized medium,
60 a modulating valve assembly connected to the second conduit means,
said modulating valve assembly having a flow chamber formed therein and said flow chamber having an inlet connected to the source of fuel,
65 an outlet connected to the gas generation means, a metering piston having three flat inwardly tapered surfaces slidably mounted in the inlet to form a plurality of flow passages therewith leading into the flow chamber,
said piston having a portion thereof normally extending into said flow chamber and being shaped so that the sliding thereof in the inlet

varies the cross-sectional fuel flow area of the piston flow passages,
 a servo motor connected to the piston to slide said piston in the inlet to vary the cross-sectional fuel flow area of the piston flow passages, and a control system connected to the gas generation means and to the servo motor
 whereby said fuel flow area is varied to maintain a pre-selected fuel feed rate to the gas generator in accordance to the desired gas generator output.

2. A gas generation system adapted for use in airborne, space-borne vehicles and the like comprising:
 a source of fuel,
 gas generation means,
 a source of a pressurized medium,
 first conduit means connecting the source of pressurized medium and the source of fuel to pressurize said fuel
 a pressure regulating valve connected to said first conduit means to regulate the flow of the pressure medium to the fuel source to supply the fuel source with a constant predetermined pressurization level,
 a second conduit means connecting said source of fuel with said gas generation means to deliver fuel to said gas generation means,
 means connected to the gas generation means to deliver a portion of the discharge gas from the gas generation means to the source of pressurized medium to maintain the supply of pressurized medium, a modulating valve assembly connected to the second conduit means,
 said modulating valve assembly having a flow chamber formed therein and said flow chamber having an inlet connected to the source of fuel,
 an outlet connected to the gas generation means, a metering piston having three flat inwardly tapered surfaces slidably mounted in the inlet to form a plurality of flow passages therewith leading into the flow chamber,
 said piston having a portion thereof normally extending into said flow chamber and being shaped so that the sliding thereof in the inlet varies the cross-sectional fuel flow area of the piston flow passages,
 a metering cam guide track slidably mounted in said flow chamber and having an end thereof connected to an end of said piston to slidably move said piston when said track moves, an offset cam connected to said guide track, a shaft extending into the flow chamber and having one end connected to said offset cam wherein in oscillation of the shaft causes the guide track to slide,
 a servo motor connected to the other end of the shaft to oscillate said shaft, and a control system connected to the gas generation means and to the servo motor
 whereby said fuel flow area is varied to maintain a pre-selected fuel feed rate to the gas generator in accordance to the desired gas generator output.

3. A gas generation system adapted for use in airborne, space-borne vehicles and the like comprising:
 a source of fuel,
 gas generation means,
 a source of a pressurized medium,
 first conduit means connecting the source of pressurized medium and the source of fuel to pressurize said fuel
 a pressure regulating valve connected to said first conduit means to regulate the flow of the pressure medium to the fuel source to supply the fuel source with a constant predetermined pressurization level,
 a second conduit means connecting said source of fuel with said gas generation means to deliver fuel to said gas generation means,

third means connected to the gas generation means to deliver a portion of the discharge gas from the gas generation means to the source of pressurized medium to maintain the supply of pressurized medium, said third means comprising
 means to cool the portion of the discharge gases being delivered to the source of pressurized medium, and
 check valve means to control the amount of discharge gases delivered to said source of pressurized medium,
 a modulating valve assembly connected to the second conduit means,
 said modulating valve assembly having a flow chamber formed therein and said flow chamber having an inlet connected to the source of fuel, an outlet connected to the gas generation means, a metering piston having three flat inwardly tapered surfaces slidably mounted in the inlet to form a plurality of flow passages therewith leading into the flow chamber, said piston having a portion thereof normally extending into said flow chamber and being shaped so that the sliding thereof in the inlet varies the cross-sectional fuel flow area of the piston flow passages,
 a metering cam guide track slidably mounted in said flow chamber and having an end thereof connected to an end of said piston to slidably move said piston when said track moves, a shaft extending into the flow chamber and having one end connected to said offset cam wherein in oscillation of the shaft causes the guide track to slide,
 a servo motor connected to the other end of the shaft to oscillate said shaft, a control system connected to the gas generation means and to the servo motor
 whereby said fuel flow area is varied to maintain a pre-selected fuel feed rate to the gas generator in accordance to the desired gas generator output.

4. A gas generation system adapted for use in airborne, space-borne vehicles and the like comprising:
 a source of fuel,
 gas generation means,
 a source of a pressurized medium,
 first conduit means connecting the source of pressurized medium and the source of fuel to pressurize said fuel
 a pressure regulating valve connected to said first conduit means to regulate the flow of the pressure medium to the fuel source to supply the fuel source with a constant predetermined pressurization level,
 a second conduit means connecting said source of fuel with said gas generation means to deliver fuel to said gas generation means,
 third means connected to the gas generation means to deliver a portion of the discharge gas from the gas generation means to the source of pressurized medium to maintain the supply of pressurized medium, said third means having
 cooling means to cool the portion of discharge gases being delivered to the source of pressurized medium, and
 check valve means to control the amount of discharge gases delivered to said source of pressurized medium,
 a modulating valve assembly connected to the second conduit means,
 said modulating valve assembly having a flow chamber formed therein and said flow chamber having an inlet connected to the source of fuel, an outlet connected to the gas generation means, a metering piston having three flat inwardly ta-

perforated surfaces slidably mounted in the inlet to form a plurality of flow passages therewith leading into the flow chamber,
 said piston having a portion thereof normally extending into said flow chamber and being shaped so that the sliding thereof in the inlet varies the cross-sectional fuel flow area of the piston flow passages,
 a metering pin cam guide track slidably mounted in said flow chamber and having an end thereof integrally connected to an end of said piston to slidably move said piston when said track moves,
 a slot provided across the width of the guide track, an offset cam means connected to the shaft having a cylindrical leg and an offset rectangular cross-sectional leg,
 bearing means surrounding said cylindrical leg, said cylindrical leg and said bearing means connected to said guide track slot and means maintaining said bearing means and cylindrical leg therein,
 a shaft extending into the flow chamber and having one end connected to said rectangular leg wherein oscillation of the shaft causes the guide track to slide,
 a servo motor connected to the other end of the shaft to oscillate said shaft,
 a control system connected to the gas generation means and to the servo motor whereby said fuel flow area is varied to maintain a pre-selected fuel feed rate to the gas generator in accordance to the desired gas generator output.

5. A gas generation system comprising:

a source of fuel,
 gas generation means,
 a source of a pressurized medium,
 first conduit means connecting the source of pressurized medium and the source of fuel to pressurize said fuel,
 a pressure regulating valve connected to said first conduit means to regulate the flow of the pressure medium to the fuel source to supply the fuel source with a constant predetermined pressurization level,
 a second conduit means connecting said source of fuel with said gas generation means to deliver fuel to said gas generation means,
 a modulating valve assembly connected to the second conduit means,
 said modulating valve assembly having a flow chamber formed therein and said flow chamber having an inlet connected to the source of fuel,
 an outlet connected to the gas generation means,
 a metering piston having a plurality of flat inwardly tapered surfaces slidably mounted in the inlet to form a plurality of flow passages therewith leading into the flow chamber,
 said piston having a portion thereof normally extending into said flow chamber and being shaped so that the sliding thereof in the inlet varies the cross-sectional fuel flow area of the piston flow passages,

a servo motor connected to the piston to slide said piston in the inlet to vary the cross-sectional fuel flow area of the piston flow passages, and a control system connected to the gas generation means and to the servo motor whereby said fuel flow area is varied to maintain a pre-selected fuel feed rate to the gas generator in accordance to the desired gas generator output.

6. A gas generation system comprising:

a source of fuel,
 gas generation means,
 a source of a pressurized medium,
 first conduit means connecting the source of pressurized medium and the source of fuel to pressurize said fuel,
 a pressure regulating valve connected to said first conduit means to regulate the flow of the pressure medium to the fuel source to supply the fuel source with a constant predetermined pressurization level,
 a second conduit means connecting said source of fuel with said gas generation means to deliver fuel to said gas generation means,
 means connected to the gas generation means to deliver a portion of the discharge gas from the gas generation means to the source of pressurized medium to maintain the supply of pressurized medium,
 a modulating valve assembly connected to the second conduit means,
 said modulating valve assembly having a flow chamber formed therein and said flow chamber having an inlet connected to the source of fuel,
 an outlet connected to the gas generation means,
 a metering piston having a plurality of tapered surfaces slidably mounted in the inlet to form a plurality of flow passages therewith leading into the flow chamber,
 said piston having a portion thereof normally extending into said flow chamber and being shaped so that the sliding thereof in the inlet varies the cross-sectional fuel flow area of the piston flow passages,
 a servo motor connected to the piston to slide said piston in the inlet to vary the cross-sectional fuel flow area of the piston flow passages, and a control system connected to the gas generation means and to the servo motor whereby said fuel flow area is varied to maintain a pre-selected fuel feed rate to the gas generator in accordance to the desired gas generator output.
